WEATHER STRIP AND SASH MOUNTING

Arthur M. Starek, Springdale, Conn.

Application February 24, 1941, Serial No. 380,266

1 Claim. (Cl. 20—12)

This invention relates to window constructions and relates more particularly to parting strip constructions for window jambs which permit ready removal or tilting of the window sash or sashes to facilitate access to the exteriors thereof.

The sashes of windows usually are mounted in guideways formed by the window jamb, a parting strip and an inner or outer guide strip. In the most common form of window structure, parting and other guide strips are nailed to the jamb to secure the sashes in position.

Inasmuch as it is difficult to gain access to the exterior of such sashes from the interior of the building for washing or cleaning, numerous constructions have been suggested for demountably supporting the sashes in the jamb or for swinging the sashes relatively to the jamb.

The present invention has as an object the provision of an improved form of parting strip for window constructions which permits ready removal or swinging of the window sashes.

Another object of the invention is to provide an improved form of parting strip which may be easily assembled and disassembled in order to facilitate its installation and repair.

A further object of the invention is to provide a parting strip which is simple in construction, positive in its retention of the window sashes and which acts to seal the sash in weather-tight relationship to the jamb.

Other objects of the invention will become apparent from a description of a typical form of the invention.

For a better understanding of the present invention reference may be had to the accompanying drawing in which:

Figure 1 is a view in vertical section of the typical form of window construction embodying the present invention; and

Figure 2 is a view in section taken along line 2—2 of Figure 1.

Parting strips of the type embodying the present invention are illustrated in the drawing as applied to the type of window sash and counterbalance construction disclosed in my copending application Serial No. 373,886, filed January 10, 1941. It will be understood, of course, that the parting strip construction may be applied with equal facility to other types of window constructions.

As best shown in Figure 1, a typical form of window having a parting strip embodying the present invention applied thereto may consist of a jamb 10 of sufficient width to accommodate two

vertically slideable sashes 11 and 12. The sashes 11 and 12 may be supported in any intermediate position by means of spiral type counterbalances 13 of well-known form. These counterbalances are provided with rods, not shown, to which are pivotally secured hinge-like elements 14 which permit the sashes to be rotated or swung about their lower edges from a vertical position to the horizontal dotted line positions shown in Figure 1.

The sash 11 may be normally retained in its vertical position by means of a guide member 15 which consists of an elongated strip disposed in a recess 16 in the jamb and normally urged outwardly to overlap the edge of the sash 11 by means of a plurality of springs 17. The outer sash 12 is prevented from swinging outwardly by means of a facing strip secured to the outer edge of the jamb and overlying the edge of the sash 12.

The construction described above permits swinging movement of the inner sash 11 from a vertical to a horizontal position by pressing the strip 15 into the recess 16.

If a parting strip of conventional form, that is, a strip nailed to the jamb, were provided between the sashes it would not be possible to swing the outer sash inwardly because the parting strip would block inward movement of the sash 12.

In accordance with the present invention a parting strip construction 18 is provided which may be moved into a position flush with the inner surface of the jamb 10, thereby permitting the sash 12 to be swung into the room when lowered to the dotted line position and the inner sash 11 is swung inwardly.

As best shown in Figure 2, a typical form of parting strip 18 embodying the present invention may consist of an elongated channel member 19 which is adapted to be secured in a recess 20 between the spiral balances 13 by means of screws 21. The channel member preferably is of unitary construction, but, if desired, it may be made up of a plurality of parts. The side walls 22 and 23 of the channel member are provided with inwardly directed flanges 24 and 25 which are inclined at an acute angle to the respective side walls.

Cooperating with the channel member 19 is an elongated shell member 26 formed of resilient material which is provided with a central generally rectangular raised portion 27 forming the parting strip proper and which is of sufficient width to be received closely between the adjacent edges of the sashes 11 and 12. Outwardly of the

raised portion 27 are longitudinally extending ribs 28 and 29 which are receivable in grooves 30 and 31 in the window sashes 11 and 12. The shell member 26 is also provided with rearwardly projecting flanges 32 and 33 which have at their edges flanges 34 and 35 inclined generally complementally to the inclination of the flanges 24 and 25 on the channel member 19.

Interposed between the base of the channel member 19 and the shell member 26 are a plurality of springs 36 which normally urge the shell member 26 outwardly toward the open side of the channel member 19 and into engagement with the edges of the window sashes 11 and 12. The springs 36 may be of any desired type and may be secured to the channel member 19, for example, by soldering or by means of tabs stuck out of the bottom of the channel member.

With this construction a normally weather-tight seal is maintained between the shell 26 and the edges of the sashes 11 and 12 and inasmuch as a constant pressure is exerted on the edges of the sashes, rattling of the sashes in the jambs is minimized and the sashes and jamb may expand or contract due to varying weather conditions without the seal being broken.

Parting strip constructions of the type described above may be very readily installed in window jambs inasmuch as the elements thereof may be readily taken apart and assembled. For example, the channel member may be placed in the groove 20 and secured in position by means of the screws 21. One flange, for example flange 35, of the shell member 26, may then be inserted behind the flange 24 of the channel member and the shell member 26 compressed so that the flange 34 can be pushed by the flange 25 on the channel member thereby securing these elements together. The flexibility of the side walls of the channel member 19 also facilitates the insertion of the shell member 26 into the channel member. Similarly by compressing the shell member 26 transversely, it is possible to detach the shell from the channel member 19 if it is necessary to make repairs to or replace any part thereof.

From the foregoing description it will be ap-

parent that a simple parting strip construction has been provided which may be readily applied to window jamb and window sash constructions and which, when installed, permits ready removal or inward swinging of the outer sash into the building for access to its outer surface.

It will be understood, of course, that parting strips of the type embodying the invention are susceptible to considerable modification as to form and contour and shape and size and that they may be used for example, to replace the strip 15, if desired, or for other purposes of similar nature, without departing from the invention. Accordingly, the form of parting strip disclosed herein should be considered as illustrative only and not as limiting the scope of the following claim.

I claim:

A parting strip construction for window jambs comprising a pair of retaining members adapted to be mounted in spaced apart, substantially parallel relationship in a longitudinally extending recess in a window jamb, inwardly extending flanges on said retaining members adjacent to their outer edges defining a restricted opening extending longitudinally of said recess, a combined parting and weather strip adapted to be detachably mounted in said recess, said parting and weather strip comprising a substantially U-shaped channel member having substantially parallel sidewalls projecting inwardly between and substantially parallel to said retaining members and a bottom interposed between said sidewalls, flanges projecting outwardly from said sidewalls behind the flanges on said retaining members for retaining said channel member in said recess, a large rib of generally rectangular cross-section projecting from the middle and extending longitudinally of said base in a direction opposite to said sidewalls and forming a parting strip, smaller ribs projecting from said base on opposite sides of said parting strip engageable with edges of window sashes on opposite sides of said parting strip to form weather strips, and means for urging said channel member outwardly of said recess.

ARTHUR M. STARCK.
